UNITED STATES PATENT OFFICE

167,031

WASHER FOR HYPODERMIC SYRINGE
OR THE LIKE

William W. Gallagher, Jr., Weston, Mass.

Application October 20, 1950, Serial No. 12,635

Term of patent 14 years

(Cl. D83—1)

To all whom it may concern:

Be it known that I, William W. Gallagher, Jr., a citizen of the United States, residing at Weston, in the county of Middlesex and Commonwealth of Massachusetts, have invented a new, original, and ornamental Design for a Washer for Hypodermic Syringe or the like, of which the following is a specification, reference being had to the accompanying drawing, in which the single figure is a perspective view of the washer for hypodermic syringe or the like embodying my new design.

I claim:

The ornamental design for a washer for hypodermic syringe or the like, as shown.

WILLIAM W. GALLAGHER, JR.
